UNITED STATES PATENT OFFICE

BENJAMIN F. SCHMIDT, OF LOS ANGELES, CALIFORNIA, ASSIGNOR TO SCHMIDT PRODUCTS, INCORPORATED, OF DETROIT, MICHIGAN, A CORPORATION OF MICHIGAN

SHOTGUN SHELL

Application filed April 18, 1927. Serial No. 184,537.

This invention relates to the ammunition art and particularly to cartridges or shells used in connection with shot guns.

The object of the invention is to produce a cartridge which will have introduced into the wrapper or base thereof certain friction means which will hold the shell from sliding out of the breech of a double barreled or like type of shot gun when the same is being loaded, without in any way interfering with the proper ejecting of the shells from that type of gun, or from other types of breech loading guns such as the automatic or pump guns.

Under present day shooting conditions a large amount of shooting is done from blinds in which the shooter is confined in a tank or box, which prevents the breaking of the double barreled or like gun within the blind, except by holding the barrel at an inclination projecting above or below the top edge of the blind. When held at this inclination the present-day commonly used loaded shells tend to slip out of the open ends of the breech by gravity, and this makes it very hard to properly load the gun from within the blind and necessitates the shooter standing up so that he may break the gun above the level of the blind to either hold the barrel of the gun parallel with or at a downward inclination to the horizon so he can drop the shells into position without their tending to fall out of the barrel. This causes a great deal of inconvenience and loss of time, and also many times tends to frighten away approaching game, and is a condition which is found very objectionable to most hunters.

My improved invention, however, is designed to provide a friction means on the base or wrapping of the shell which will hold the loaded shells in frictional contact with the sides of the barrels of the gun and prevent their tending to slide out by gravity, but which will under the pressure caused by the explosion of the shell flatten or be eradicated so as not to interfere with the easy ejecting of the shells from the breech of the gun either in a double barreled, pump or automatic gun.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawings similar characters of reference indicate corresponding parts in the several views:

Fig. 1 is a side elevation of a shot gun shell showing the preferred form of my invention in connection therewith.

Fig. 2 is a sectional view taken on a line 2-2 of Fig. 1.

Figs. 3, 4, 5, and 6 are side elevations of shells showing slightly modified forms in which my improved invention could be applied to the shell.

Referring now more particularly to the characters of reference on the drawings, the numeral 1 designates the usual metal base of the shell and the numeral 2 the upper cardboard wrapped portion of the shell.

My improved invention consists of a series of slight protuberances or swells 3 formed preferably in the base 1 of the shell and made by cutting small slots 4 in the surface of the base and then pressing out the material on the outside of the slot to form the protuberances 3. These protuberances will be very slight but when the shell is being forced into the breech of the gun, will have a certain resilient friction which will be just great enough to prevent the shell from tending to drop out of the breech of the gun by gravity. With the explosion of the shell however these will be instantly flattened out with the pressure of the explosion so as not to interfere with the ready ejecting of the shell from any type of gun.

While the friction means shown will be entirely sufficient to prevent the shell from tending to drop by gravity from the breech of the gun under the conditions noted in the preamble to this specification, still the size and shape thereof will not be sufficient to interfere with the rapid loading of any breech loading gun, or interfere with the

satisfactory use in repeating or automatic guns.

In Fig. 3 the protuberances 3a are made merely by a slight swelling out of the material of the base circumferentially of the same.

In Fig. 4 the protuberances 3b are made by the slight swelling out of the base of the shell longitudinally of the same, and in Fig. 5 the protuberances 3c are formed by slightly swelling out the cardboard wrapping of the shell rather than the metal base.

These modified forms as disclosed give a slight idea of how various modifications of the exact form of construction of the friction means may be had without in any way departing from the spirit of the invention, and I do not wish to confine myself to any particular method of manufacture of the shell embodying my invention, since, as is obvious, many modifications thereof may be indulged in without departing from the spirit of the invention.

In the modification shown in Fig. 6 instead of having the protuberances shown in the other forms, I provide at the top of the shell a plurality of projections or lips 3d put under spring tension and having their upper ends turned inwardly to prevent any possibility of the same catching the sides of the gun barrel. These small spring lips will also give the necessary resiliency to frictionally hold the shell in place against dropping out by gravity and at the same time after the explosion of the shell they will be flattened out so that the shell may be readily ejected.

Having thus described my invention what I claim as new and useful and desire to secure by Letters Patent is:

1. A gun cartridge of the type described comprising a slight protuberance on the outer surface of the shell of the cartridge to frictionally engage the gun barrel, such protuberance being so formed that the pressure of the shell against the gun barrel occasioned by the firing of the cartridge will flatten the same into the plane surface of the shell.

2. A gun cartridge of the type described comprising a means integral with the shell of the cartridge to cause a resilient frictional engagement of the shell with a gun barrel sufficient to keep it from sliding out of the breech of the gun when the barrel is vertically inclined.

3. A gun cartridge of the type described comprising a means integral with the shell of the cartridge to cause a resilient frictional engagement of the shell with a gun barrel sufficient to keep it from sliding out of the breech of the gun when the barrel is vertically inclined, such means being so arranged that the expansion of the shell occasioned by the firing of the cartridge will

flatten the same to relieve the resilient frictional engagement to such an extent as to allow the free normal or automatic ejection of the discharged shell from the gun barrel.

4. A gun shell for use in the break breech type of shot guns comprising an element on the outer surface of the body of the shell of slightly greater diameter than the diameter of the shell whereby when the shell is inserted into the breech of the gun such element will frictionally engage the walls of the gun barrel and prevent the shell from slipping out of the gun barrel by gravity; the element being of such construction that upon the firing of the shell, the percussion will flatten the element to a diameter substantially that of the shell body.

In testimony whereof I affix my signature.

BENJAMIN F. SCHMIDT.
